UNITED STATES PATENT OFFICE.

FRANK C. HORN, OF BOISE, IDAHO.

CEMENT-MIXER.

1,047,636.

Specification of Letters Patent. Patented Dec. 17, 1912.

Application filed September 17, 1912. Serial No. 720,749.

To all whom it may concern:

Be it known that I, FRANK C. HORN, a citizen of the United States, residing at Boise, in the county of Ada and State of Idaho, have invented certain new and useful Improvements in Cement-Mixers, of which the following is a specification.

My invention relates to improvements in cement mixers, and refers particularly to 10 that type of cement mixers using compressed air as the moving agent.

The primary object of the invention is to provide a cement mixer in which the cement in a dry state may be introduced into the 15 mixing chamber and thoroughly commingled with the water to reduce the same to a plastic, semi-liquid, or liquid state by means of air under pressure.

Another object of the invention is to provide a cement mixer which will be of the 20 simplest and most inexpensive construction to insure a thoroughly practical and efficient device of this kind; which will thoroughly and reliably commingle the cement and 25 water and deliver the same under pressure out of a discharge nozzle by the use of compressed air as a mixing and carrying agent; and which will in general prove desirable and efficient from every point of view.

To attain the desired objects, the invention broadly stated consists of a mixing chamber, means for separately introducing cement and water thereinto, and pneumatic means for mixing and discharging said mixture from said chamber, the invention further consisting of certain novel features of construction and arrangements of parts, substantially as shown, described and claimed hereinafter, reference being had to the accompanying drawing, in which—

Figure 1 is a side elevation of a mixer constructed in accordance with and embodying the principles of the invention, the parts above the central longitudinal line 45 A—A being shown in section, and those parts below said line being shown in elevation, and Fig. 2 is a vertical sectional view on line 2—2 of Fig. 1, looking at the mixer from the discharge end thereof.

Referring more specifically to the drawings, in which similar characters of reference denote corresponding parts in the views:—The letter A designates a cylindrical jacket forming a space B to contain 55 the water supplied thereto by means of the connection C with a suitable water supply.

The jacket A is closed at each end by the stuffing boxes D threaded thereon, and a perforated pipe E is arranged within said jacket and has a multiplicity of perforations F for admitting water under pressure from the water space into the interior of the pipe. This pipe has an extension G, and a connection G' is threaded thereonto at one end through which the cement or other mixture in a dry state is introduced, and said pipe is further provided with an extension H, which has a connection H' threaded onto one of its ends through which the air under pressure passes to thoroughly commingle the water and cement and discharge the same out of the other end of the pipe or mixing chamber E, onto which end is threaded a discharge nozzle J to secure concentration of the materials and line of direction. A drain cock K is provided for the water jacket, as shown. From this construction it will be seen that the water is supplied to the water circulation space B by means of the connection C, and that the water enters the mixing chamber E under pressure through said perforations F, where it is commingled with the dry cement fed into said chamber through the connection G of the hopper or other receptacle (not shown) by means of the compressed air delivered into said chamber through the connection H. The water and cement are thus thoroughly mixed by the air and are conveyed to the forward end of the chamber thereby and are discharged through the nozzle J upon the walls or other surface to be filled. The amount of water or cement admitted to the chamber may be controlled in any suitable manner to render the mixture plastic, semi-liquid, or liquid, as desired.

From the foregoing description, taken in connection with the accompanying drawings, the construction and operation of my improved cement mixer will be readily seen and understood.

I claim:—

1. A cement mixer, comprising a mixing chamber having a perforated shell, a jacket surrounding said mixing chamber forming a water chamber in communication with said mixing chamber, means for supplying material to said mixing chamber, means for supplying water to said water chamber, and means for exerting a pneumatic pressure upon the materials in said mixing chamber.

2. A cement mixer, comprising a cyl-

drical mixing chamber having a perforated shell; a cylindrical jacket surrounding said mixing chamber forming a water chamber in communication with said mixing chamber, a connection to supply water under pressure to said water chamber, a connection to supply material in a dry state at one end of the mixing chamber, and a connection at

one end of said mixing chamber to supply air under pressure to said mixing chamber. 10

In testimony whereof I affix my signature in presence of two witnesses.

FRANK C. HORN.
